UNITED STATES PATENT OFFICE.

ARTHUR W. EASTON, OF BUFFALO, NEW YORK.

COMBINED CIGARETTE HOLDER AND EJECTOR.

Application filed July 27, 1926. Serial No. 125,208.

This invention relates to improvements in a combined cigar or cigarette holder and ejector therefor.

One of its objects is to provide a device of this character whose parts are so organized and arranged as to readily and quickly effect the removal of the cigar or cigarette stub without the smoker's hands coming in contact therewith.

Another object of the invention is the provision of a combined holder and ejector which is simple and compact in construction and which can be manufactured at a moderate cost.

In the accompanying drawings:

Figure 1 is a side elevation of a combined holder and ejector embodying my invention. Figures 2, 3 and 4 are enlarged vertical longitudinal sections of the device showing the steps for effecting the ejection of a cigarette therefrom. Figures 5, 6 and 7 are transverse sections on the correspondingly numbered lines in Figs. 2, 3 and 4, respectively. Figures 8 and 9 are perspective views of the ejector-tube. Figure 10 is a vertical longitudinal section of a modified form of the invention. Figure 11 is a vertical longitudinal section of another modification of the invention. Figure 12 is a transverse section on line 12—12, Fig. 11. Figure 13 is a perspective view of the ejector-tube of the modified construction shown in Fig. 12.

Similar characters of reference indicate corresponding parts throughout the several views.

In the preferred embodiment of the invention shown in Figs. 1-9, inclusive, the improved holder comprises a mouth-piece 15 having the usual bore or smoke passage 16, a cigar or cigarette holding tube 17, and an ejecting member or tube 18, telescopically fitted within the opposing front and rear ends of the mouth-piece and the holding tube. These three parts are so organized and arranged as to permit the ejecting member to be moved lengthwise of the cigarette holding tube through the medium of the mouth-piece, which last-named part is adapted to be coupled with the ejecting member in effecting the removal of the cigar or cigarette stub or butt from its holding tube.

Slidably fitted within the enlarged front portion 19 of the mouth-piece bore 16 is the rear end of the ejector-tube 18 which is provided in its outer side with a longitudinal groove or recess 20 with which teats or pro-

jections 21, 22 formed in the bores of the opposing ends of the mouth-piece and cigarette holding tube 17, respectively, are adapted to engage. At its rear end, this longitudinal groove is deflected part way around the ejector-tube to form a diagonal or spiral-like extension 23, which terminates at its end in a transverse portion 24 with which the teat 21 of the mouth-piece is adapted to automatically engage for the purpose of positively coupling or interlocking the ejector-tube with the mouth-piece when it is desired to displace the cigar or cigarette from the holding-tube 17. In order to readily facilitate the assembling of the various parts of the holder, the ejector-tube is provided in its outer side with a longitudinal groove 25 extending from end to end thereof and arranged parallel with and suitably spaced from the longitudinal portion 20 of the spiral groove. Said groove 25 is connected with the latter by a transverse groove 26, as shown in Figs. 6, 8 and 9. Thus, in assembling the parts, the ejector-tube is inserted in the mouth-piece with its longitudinal groove 25 engaging the mouth-piece teat 21; when the latter is brought opposite the transverse connecting groove 26, the parts are turned relatively to each other to bring said teat into register with the other longitudinal groove 20 of the ejector-tube. The holding-tube 17 is now fitted over the extended front end of the ejector-tube, its teat 22 being first engaged with the longitudinal groove 25 of said ejector-tube, then with the transverse groove 26 and finally with the longitudinal portion 20 of the spiral groove.

It will be noted that the cigarette holding tube 17 projects a suitable distance beyond the front end of the ejector-tube 18 to reliably support the cigarette therein, and that the combined length of the longitudinal groove 20 and its spiral portion 23 is somewhat longer than the projected portion of said holding tube, the effective stroke of the 100 ejector-tube relative to the latter being determined by the location of the teat 21 of the mouthpiece with reference to the transverse end portion 24 of the said groove 20-23 in the normal position of the parts. As shown in 105 the drawings, particularly Fig. 2, the distance between the mouth-piece teat and the transverse portion of the spiral groove of the ejector tube is approximately equal to the distance between the projected front end of the holding-tube and the corresponding end of the ejector-tube.

In using this improved holder for smoking, the cigar or cigarette is placed in the projected front portion of the holding-tube 17. When it is desired to remove the stub or butt therefrom, the user grasps the holding tube with one hand and the mouthpiece with the other, first pulling these members apart, by a combined rotary and longitudinal movement, to the position shown in Fig. 3, wherefore in the teat 21 of the mouth-piece is brought into interlocking engagement with the transverse end portion 24 of the spiral-groove 23 in the ejector-tube. Upon now shifting the mouth-piece forwardly relatively to the holding-tube, the ejector-tube is compelled to move lengthwise therewith to the front end of said holding-tube to the position shown in Fig. 4, with the result that the cigarette stub is ejected from the holder. The parts may be set in their initial position by reversing the steps just described for the ejecting operation, or by turning the mouth-piece relative to the holding-tube while the parts are in their ejected position shown in Fig. 4, which movement will cause the ejector-tube to be retracted into the mouthpiece owing to the engagement of the teat 21 of the latter with the spiral groove of the ejector-tube. The teat 22 of the holding-tube is always engaged with the longitudinal groove 20 of the ejector-tube, whereby relative turning of these parts during the turning of the mouth-piece on the ejector-tube is effectually prevented.

In the modification of the holder shown in Fig. 10, the front end of the ejector-tube has a reduced stem 27 and encircling the same is a coil spring 28 bearing at one end against the resulting shoulder 29 formed between the main portion of the ejector-tube and its stem, and at the other end against an internal shoulder 30 formed in the bore of the cigarette holding tube 31. The end of the stem has a removable head 32 thereon which is normally held against the front side of said shoulder by the spring 28. The latter tends constantly to hold the cigarette holding tube and the ejector-tube in the normal relative position shown in Fig. 10, and after the operation of ejecting the cigarette stub from the holder has been performed, this spring automatically returns the ejector-tube into the mouth-piece.

In the modified form of the invention shown in Figs. 11, 12 and 13, the mouthpiece 33 has an inner tube 34 formed integral therewith which projects a suitable distance beyond the front end thereof. On its surface and near its front end, this inner mouthpiece tube has a teat or projection 35 which engages a corresponding L-shaped groove 36 in the inner side of an ejecting member 37. This ejecting member consists of an arcuate shaped bar 38 containing the groove 36 and terminates at its front end in a perforated plug or plunger 39 against which the cigarette nor-

mally abuts and which also acts to eject the cigarette from the holding-tube 40. The operation of this holder is the same as that described in the first embodiment of the invention.

I claim as my invention:—

1. A cigarette holder, comprising a mouth-piece, a cigarette-holding tube separate from the mouthpiece, an ejecting member telescopically fitted in the opposing front and rear ends of said mouthpiece and said holding tube, the mouthpiece being movable relatively to both the ejecting member and the holding tube in one direction, and means for coupling said mouthpiece to said ejecting member to shift the latter relatively to said holding tube in the opposite direction to eject the cigarette therefrom. 70

2. A cigarette holder, comprising a mouth-piece, a cigarette-holding tube separate from the mouthpiece, an ejecting member telescopically fitted in the opposing front and rear ends of said mouthpiece and said holding tube and movable lengthwise of the latter, the mouthpiece being movable on the ejecting member to a predetermined position in spaced relation to the opposing end of the holding tube, and complementary means on said mouthpiece and said ejecting member for coupling such parts as a unit in said predetermined position to slide said ejecting member in the holding tube to eject the cigarette. 80

3. A cigarette holder, comprising a mouth-piece, a cigarette-holding tube separate from the mouthpiece and normally abutting at one end against the latter, an ejecting member telescopically fitted in the opposing front and rear ends of said mouthpiece and said holding tube, the holding tube being held from rotation relative to the ejecting member and the mouthpiece being slidable and rotatable on the ejecting member, and means for coupling said mouthpiece to said ejecting member to shift the latter relatively to said holding tube to eject the cigarette therefrom. 100

4. A cigarette holder, comprising a cigarette holding tube, an ejecting member slidable therein and having a longitudinal groove and a connecting spiral groove, and a mouthpiece slidable lengthwise on the ejecting member and having a projection normally engaging with said longitudinal groove and adapted to engage said spiral groove to couple the mouthpiece to the ejecting member. 115

5. A cigarette holder, comprising a cigarette-holding tube, an ejecting member slidable therein and having an external longitudinal groove and a connecting spiral groove, and a mouthpiece slidably and rotatably mounted on the ejecting member and having a projection normally engaged with said longitudinal groove and adapted to be shifted rearwardly on the ejecting member to engage its spiral groove and compel the eject- 125

ing member to slide with the mouthpiece in a forward direction.

6. A cigarette holder, comprising a cigarette-holding tube, an ejecting member slid-
5 able therein and having a connecting longitudi-
nal and spiral groove, the rear end of said
spiral groove terminating in a transverse
portion, and a mouthpiece mounted on the
ejecting member and having a projection nor-
10 mally engaging said longitudinal groove and
adapted to traverse said spiral groove and
interlock with the transverse portion thereof
upon a rearward and rotary movement of the
mouthpiece relative to the ejecting member.
15 7. A cigarette holder, comprising a hold-
ing tube, a mouthpiece separate from the
holding tube and normally abutting endwise
against the same to form a closed joint, a com-
bined coupling member and ejector fitted in
20 the opposing ends of said holding-tube and
said mouthpiece, the latter being movable
lengthwise on said coupling member in a di-

rection to separate the joint between it and
the holding-tube, and complementary inter-
locking devices on the mouthpiece and the 25
coupling member for connecting such parts
as a unit and compelling their simultaneous
movement in the opposite direction to close
the joint, said coupling member being slid-
able in said holding-tube during such move- 30
ment for ejecting the cigarette therefrom.

8. A cigarette holder, comprising a hold-
ing tube, a mouthpiece separate from the
holding-tube, a combined coupling member
and ejector relatively movable in the oppos-
ing ends of the holding tube and the mouth-
piece, and a tongue and groove connection be-
35 tween said mouthpiece and said ejector, the
former being slidable on the latter in one di-
rection and said ejector being movable with
the mouthpiece through the holding tube in
the opposite direction to eject the cigarette
40 therefrom.

ARTHUR W. EASTON.
